UNITED STATES PATENT OFFICE.

PHILIP C. MERKER, OF CEDAR RAPIDS, IOWA.

CAR-DOOR.

1,086,602.

Specification of Letters Patent.

Patented Feb. 10, 1914.

Application filed November 22, 1911. Serial No. 661,740.

To all whom it may concern:

Be it known that I, PHILIP C. MERKER, a citizen of the United States, residing at Cedar Rapids, in the county of Linn and State of Iowa, have invented a new and useful Car-Door, of which the following is a specification.

The invention relates to improvements in car doors.

10. The object of the present invention is to improve the construction of car doors, and to provide a simple, efficient and comparatively inexpensive car door, designed for use on grain cars and various other freight cars for carrying different kinds of merchandise, and adapted when closed to fit snugly the interior of the car to form a storm-proof and grain tight closure, and capable of opening exteriorly of the car without the 20 contents of the car interfering with such movement.

The invention also has for its object to provide a door of this character, adapted to fold in a compact position on the outside 25 of the car so as to be out of the way of other cars when the tracks are close together, and also to be clear of platforms and various other constructions at grain elevators and other places.

30. With these and other objects in view, the invention consists in the construction and novel combination of parts hereinafter fully described, illustrated in the accompanying drawings, and pointed out in the claims hereto appended; it being understood that 35 various changes in the form, proportion, size and minor details of construction, within the scope of the claims, may be resorted to without departing from the spirit or sacrificing any of the advantages of the invention.

In the drawings:—Figure 1 is a front elevation of a car door, constructed in accordance with this invention, and shown 45 applied to a car. Fig. 2 is a vertical section view on the line 2—2 of Fig. 1. Fig. 3 is a horizontal sectional view on the line 3—3 of Fig. 1. Fig. 4 is a horizontal sectional view on the line 4—4 of Fig. 1. Fig. 5 is a vertical sectional view on the line 5—5 of Fig. 4. Fig. 6 is a detail perspective view of the lower hasp and bracket for locking the pivoted door engaging bar. Fig. 7 is a similar view of the upper hasp member 55 and the seal receiving pin.

Like numerals of reference designate cor-

responding parts in all the figures of the drawings.

In the accompanying drawings in which is illustrated the preferred embodiment of 60 the invention, the car door comprises in its construction an upper door 1 and a main or lower door, composed of four vertical door sections 2, 3, 4 and 5, but the number of vertical sections of the lower or main 65 door may be increased to provide a door of the desired size, or the vertical sections may be varied in size to secure the same result. The door sections 2 and 3 are hinged together and the door sections 4 and 5 are 70 likewise hinged together, forming two sectional doors, which extend from the bottom of the door opening of the side or wall 6 of the car into the upper half of the door opening, the upper door 1 being in 75 the nature of an auxiliary door, adapted to be opened for loading grain and designed to remain closed when the merchandise contained within the car is of a size to pass through the door opening when the 80 lower or main door only is opened.

The sections 2 and 5 of the sectional doors are slidably connected with vertical pintle rods 7 by hinge elements composed of two leaves 8 and 9, hinged together by a vertical pintle 10 and adapted to permit the sectional doors to swing through the door opening of the car from the interior to the exterior of the same and vice versa. The leaves 8 are riveted or otherwise secured to 85 the outer faces of the door sections 2 and 5 at points intermediate of the vertical side edges of the same, and the leaves 9, which constitute intermediate leaves, are provided with eyes 11, slidably arranged on the vertical pintle rods 7 and supported by the contiguous hinge elements or brackets 12. The vertical pintle rods 7, which are located at opposite sides of the door opening of the car, are supported at intervals by the fixed 90 hinge elements or brackets 12, provided with vertically aligned eyes to receive the pintle rods and having slots 13 through which pass bolts 14, or other suitable fastening devices for securing the hinge elements or brackets 95 12 in fixed adjustment. The bolts have their heads arranged at the inner faces of the car so as to present smooth surfaces to the contents of the same. The hinges 15, which connect the upper door 1 with the car at the 100 top of the door opening, are also provided with slots 16 for the reception of suitable 105 110

fastening devices 17 for adjustably securing the upper door 1 to the car. As the upper door and the lower or main door fit against the interior of the car when closed, they are capable of adjustment through the said slots and fastening devices to enable the door to be arranged to fit various door openings whether in or out of plumb, and it obviates the necessity of trimming the doors or the frame-work of the car for this purpose. As the sectional doors swing on the vertical pintle rods 7 and also on the pintles 10, they are adapted to be readily moved through the car door opening to and from their closed position. The hinge elements or brackets 12 are preferably four in number and spaced apart to provide upper and lower intermediate spaces for the eyes 11 of the leaves 9, and three sets of leaves 8 and 9 are employed, as shown, but the number of brackets or fixed hinge elements and the leaves 8 and 9, which constitute movable hinge elements, may be, of course, varied, as desired. The vertical sliding of the sectional doors enables the sections when folded to be lifted over supporting brackets 18.

The sections of the lower or main door and the upper door are preferably constructed of heavy sheet metal, such as boiler iron, but any other suitable material, either wood or metal, may be employed in the construction of the doors. The hinges 19 and 20, which connect the sections 2 and 3 and 4 and 5 together in pairs, are preferably arranged at the top, bottom and center of the said sections 2, 3, 4 and 5, and the hinges 19 of the sections 2 and 3 are arranged at the inner faces of the same, while the hinges 20 of the sections 4 and 5 are located at the outer faces of those sections. This permits the sections 2 and 3 to break outwardly and the sections 4 and 5 to break inwardly. The hinges 19 and 20 each consists of two channeled iron bars, extending entirely across the sections, as shown, and provided at their adjacent ends with eyes for the reception of a suitable pintle. The hinges of the vertical sections of the lower door may be constructed and arranged in any other preferred manner. The vertical sections are bent outwardly at the bottom to form horizontal bottom flanges 22, and the contiguous vertical edges of the sections 2 and 3 are bent outwardly to form abutting flanges 23 and 24, the flange 24 being L-shaped to cover the joint between the sections 2 and 3, as clearly shown in Fig. 4. The contiguous vertical edges of the sections 4 and 5 are bent outwardly to form vertical abutting flanges 25, and the section 5 is provided at its inner face with a vertical strip 26, riveted or otherwise secured to the said section 5 and spanning and covering the joint between the sections 4 and 5. The adjacent edges of the sections 3 and 4 are bent out-

wardly to form flanges 27 and 28, the flange 28 being L-shaped in cross section and overlapping the flange 27 to cover the joint.

The lower edge of the upper door extends below the upper edges of the vertical sections of the lower door, and the said upper door is equipped at its outer face adjacent to its lower edge with a horizontal flanged bar 29, having one of its flanges fitted against the upper door and suitably secured to the same, while the other flange projects horizontally from the upper door over the upper edge of the main door and against the meeting portions of the doors to provide a tight joint at the top of the lower or main door. The horizontal projecting flange is provided at intervals with slots 30, adapted to be engaged by a pointed bar, or other tool to enable the vertical sections of the lower door to be forced inwardly into position and permitting the bills of hooks 31 to project through the horizontal flange for engaging the upper ends of the vertical sections of the lower door for securing the same in tight engagement with the lower edge of the upper door and for securing the latter in its closed position. The hooks are pivoted by rivets 32, or other suitable fastening means, to the vertical flange of the horizontal bar 29, and their bills may be equipped with slots 33 for the reception of fastening means for locking the hooks in engagement with the upper end of the vertical sections of the lower door.

The car is equipped with a transversely curved sill plate 34, extending entirely across the door opening and arranged upon a wooden filler strip or bar 35, and secured to the floor of the car by wood screws, or other suitable fastening devices. The bottom flanges of the vertical sections of the lower door are arranged upon the sill plate at the center thereof, and any water is directed upon the outer slope of the sill plate and caused to flow from the door.

The lower or main door is equipped with a pivoted door engaging bar 36, constructed preferably of channeled metal and mounted on the lower portion of the vertical section 3 on a bolt 37, a washer 38 being interposed between the door engaging bar and the section 3. The bolt 37, similar to the other bolts of the door, has its head arranged inferiorly of the car so as to present a smooth surface to the contents thereof. The door engaging bar 36 is of a length to extend entirely across the sections 3 and 4 and its ends, which overlap the inner portions of the sections 2 and 5, are equipped with reversely arranged hooks 39 and 40, having flat shanks arranged between the flanges of the channeled door engaging bar 36 and riveted or otherwise secured to the web portion of the latter. Although the reversely arranged hooks 39 and 40 are shown sepa-

rate from the door engaging bar 36, yet it will be readily apparent that they may be formed integral with the same. The reversely arranged hooks are adapted to engage horizontally disposed handles 41 and 42, riveted or otherwise secured to the vertical sections 2 and 5 of the lower door and forming loops, which are adapted to perform the double function of a handle to enable the doors to be conveniently opened and closed, and as a keeper to co-act with the reversely arranged hooks in locking the sections of the lower or main door in their closed position. The hooks may also be arranged outside of the handles to permit the sections 3 and 4 to be spaced from each other a sufficient distance to afford the desired amount of ventilation, thereby providing a ventilated car. The pivoted bar 36 also engages an inverted approximately U-shaped keeper 43 open at the bottom to receive the bar 36 and consisting of an inner attaching portion, a spaced outer portion and a connecting top portion, as clearly illustrated in Fig. 2 of the drawings. The inverted U-shaped keeper is preferably flanged at the outer and top portions to strengthen it, and the lower end 44 of the outer portion is inclined to provide a flaring mouth, and the inner portion is provided below the connecting portion with a vertical rib 45, rounded at the outer face and beveled at the lower end to receive the pivoted bar, which is spaced from the outer face of the inner vertical attaching portion and from the fastening devices for securing the keeper to the section 4 of the lower or main door.

The door engaging bar is provided at one side of the pivot bolt 37 with a horizontally projecting tongue or staple member 46, secured to or formed integral with the upper flange of the bar 36 and extending outwardly beyond the flange and adapted to extend through a horizontal slot or opening 47 of a lower hinged hasp 48, mounted in opposite guide grooves 49 of a supporting bracket 50. The supporting bracket 50 consists of a horizontal bottom or body portion and upwardly extending horizontal end portions spaced apart to receive the hasp 48 and having the said guide grooves 49 closed at their outer ends 51 and opened at their inner ends to permit pivot portions 52 of the hasp 48 to be introduced into the guide grooves before the bracket 50 is secured to the vertical section 3 of the lower door. The bracket is provided with ears 53 and 54, which are secured to the said section 3 of the lower door, and the door engaging bar 60 is received between the upper ears or lugs 53 and the hasp 48, which is also provided at its inner face with a horizontal inwardly projecting flange 55, arranged to engage over the bottom flange of the pivoted bar 36, as clearly illustrated in Fig. 5 of the draw-

ings. No claim is made in the present application to the locking means *per se* for securing the horizontal door engaging bar in its closed position.

The projecting tongue or staple member 46 is provided with an opening 56, through which projects the lower end of a seal receiving pin 57, mounted on an upper hasp member 58. The upper hasp member 58 is provided at the upper end with an eye 59 to receive the lower link of a chain 60, and it has a slot 61 in its lower portion for the projecting tongue; and it fits on the latter against the outer face of the lower hasp 48. The pin 57, which retains the upper hasp member 58 on the tongue, is provided above the latter with a vertical slot 62, receiving a headed stud 63, which slidably and pivotally secures the seal receiving pin to the upper hasp member. The pin 57 is provided in its lower portion with a slot 64, and the wire 65 of a seal 66 is passed through the slot 64 and through a slot or opening 67 of an arm 68 of the upper hasp member 58, the slots 64 and 67 being in alinement when the pin 57 is at the limit of its downward movement, as clearly illustrated in Fig. 7 of the drawings. The locking pin is equipped at its upper end with a projecting lip or flange 69 to enable it to be readily grasped for lifting it out of engagement with the tongue of the locking bar 36 and for engaging it with the same. The locking mechanism enables the pivoted bar 36 to be securely fastened in engagement with the vertical sections of the lower or main door, and to be sealed with an ordinary car seal.

The chain 60 passes through upper and lower chain guides 70 and 71, and is designed to be provided at its upper end with one or more enlarged links 72, adapted to engage a hook 73 having a shank portion riveted or otherwise secured to the upper door 1. By providing a plurality of links, sufficient space may be left between the lower edge of the upper door and the upper ends of the vertical sections of the lower or main door for securing the desired ventilation. The guides 70 and 71 consist of loops and opposite attaching portions, which are suitably secured to the outer face of the section 3 of the lower door.

When the sections of the lower door are opened, they are lifted over and arranged upon the supporting brackets 18, each consisting of an inner vertical attaching portion, an upper outwardly projecting horizontal supporting portion and a central vertical bracing portion. The upper horizontal supporting portion is provided with a central enlargement 74 upon which the folded vertical sections rest, and the said sections are held against outward movement by a lug 75, which projects upwardly from the front of the horizontal supporting portion. 130

The upper door 1 swings inwardly and upwardly in opening, and it is held in its open position by means of a gravity catch, consisting of a pivoted door engaging member 76, mounted between spaced depending sides 77 of a supporting bracket 78, having a top attaching portion, which is suitably secured to one of the carlines or other portion of the top of the car. The spaced depending sides 77 are connected by upper and lower horizontal portions 79 and 80, and the pivoted door engaging member 76 is provided with a projecting rear portion or heel 81 for engaging the lower connecting portion 80 to limit the downward movement of the front engaging or supporting portion of the pivoted member 76. The upper connecting portion 79 is arranged to engage and limit the inward or rear movement of the front end of the pivoted member when the latter is swung upwardly and inwardly. The front portion of the pivoted member is arranged in the path of the lower edge of the upper door, and when the latter is swung upwardly and inwardly, it strikes the outer portion of the pivoted locking member and swings past the same, the pivoted member dropping by gravity and projecting beneath the free edge of the door and forming a support for the same. By this construction the catch for holding the upper door in its open position is automatic in its operation, and it is only necessary to swing the upper door past the pivoted member of the catch to engage the latter with the upper door.

It may be desirable in some instances when the doors are constructed of metal to line the same with paper or other suitable material to prevent the doors from sweating under changes of temperature and affecting the contents of the car.

Having thus fully described my invention, what I claim as new and desire to secure by Letters Patent, is:—

1. The combination with a car having a door opening, of a car door fitted against the inside of the car when closed and comprising sectional doors composed of a plurality of vertical sections hinged together, and means for hinging the sectional doors to the car, said means being connected with the exterior of the car and constructed to permit the door sections to swing through the door opening from the interior of the car to the exterior of the same to points beyond the door opening so as to fold the sectional doors flat against the outside of the car away from the said door opening to leave the latter clear.

2. The combination with a car having a door opening, of a car door fitted against the inside of the car when closed and comprising sectional doors composed of a plurality of vertical sections hinged together, fixed supporting brackets mounted on the

exterior of the car at opposite sides of and spaced from the door opening, and means for slidably and hingedly connecting the sectional doors with the car, said means being connected with the exterior of the car and constructed to permit door sections to swing through the door opening from the inside of the car to the exterior thereof to points beyond the door opening so as to fold flat against the outside of the car away from the said door opening with their lower ends resting upon the supporting brackets.

3. The combination with a car having a door opening, of a vertical pintle rod adjustably mounted in a fixed position on the exterior of the car at opposite sides of the door opening and spaced from the outside of the car, doors arranged against the inside of the car when closed and adjustable to cover the door opening, and hinge elements mounted on the pintle rod and connected with the doors and extending through the door opening when the said doors are closed, said hinge elements permitting the doors to swing through the door opening from the interior of the car to the exterior of the same to points beyond the door opening so as to fit flat against the outside of the car.

4. The combination with a car having a door opening, of vertical pintle rods arranged at opposite sides of the door opening at the exterior of the car, adjustable means for supporting the pintle rods in such position, fixed hinge elements secured at intervals to the exterior of the car beyond the door opening and having eyes projecting outwardly from the car and receiving the pintle rods, a car door fitted against the inside of the car and composed of sectional doors, and movable hinge elements slidably on the pintle rods and connected with the sectional doors and extending through the door opening when the said sectional doors are closed and arranged to permit them to swing through the door opening from the interior of the car to the exterior of the latter to points beyond the said door opening.

5. The combination with a car having a door opening, of vertical pintle rods arranged at opposite sides of the door opening at the exterior of the car, fixed hinge elements secured at intervals to the exterior of the car beyond the door opening and having outwardly projecting eyes receiving the pintle rods, a car door fitted against the inside of the car and composed of sectional doors, and movable hinge elements composed of two leaves hinged together and connected, respectively, with the sectional doors and with the pintle rods and extending through the door opening when the sectional doors are closed and arranged to permit them to swing through the door opening to the in-

terior of the car to the exterior of the same to points beyond the door opening.

6. The combination with a car having a door opening, of vertical pintle rods arranged on the exterior of the car at opposite sides of the door opening, fixed hinged brackets secured to the outside of the car beyond the door opening and arranged at intervals along the pintle rods and projecting outwardly from the car and supporting the said pintle rods in spaced relation with the car, a car door fitted against the inside of the car and composed of sectional doors, movable hinge elements each composed of two leaves hinged together, one of the leaves being connected to the car door and the other leaf having eyes slideable on the adjacent pintle rod and supported by the contiguous fixed hinge elements, said movable hinge elements extending through the door opening when the sectional doors are closed and permitting the latter to swing through the door opening from the interior of the car to the exterior of the same to points beyond the door opening.

7. The combination with a car having a door opening, of a lower or main door composed of sectional doors hinged to the car at opposite sides of the door opening and composed of vertical sections, an upper door hinged to the car at the top of the door opening and having its lower free edge overlapping the sections of the lower or main door, said upper door being provided at its outer face with a projecting flange extending outwardly beyond the lower or main door and covering the meeting portions thereby to form a tight joint and having slots, and fastening means carried by the upper door and arranged to project through the slots of the said flange to engage the lower or main door.

8. The combination with a car having a door opening, of a lower or main door composed of sectional doors hinged to the car at opposite sides of the door opening and having vertical sections, an upper door hinged to the car at the top of the door opening and having its lower free edge overlapping the section of the lower or main door, said upper door being provided at its outer face with a horizontal projecting flange extending across the door opening and projecting outwardly beyond the lower or main door and covering the upper edges thereof and forming a tight joint between the said doors and having slots, and pivoted hooks carried by the upper door and having bills arranged to project through the slots of the said flange to engage the lower or main door.

9. The combination with a car door comprising a pair of sectional doors composed of hinged inner and outer vertical sections, horizontal loops mounted on the outer door

sections, a hook secured to one of the inner door sections, and a substantially horizontal door engaging bar pivotally mounted on the other inner door section and engaging the said hook and provided at its terminals with reversely disposed hooks projecting upwardly and downwardly and extending into and engaging the said loops, which form keepers for the ends of the bar and handles for opening and closing the sectional doors.

10. The combination with a car having a door opening, of a lower or main door including hinged vertical sections, an upper horizontal door hinged at the top of the door opening and overlapping the lower or main door, a horizontal door engaging bar pivotally mounted on the lower or main door and engaging the sections thereof, a chain extending from the upper door to the door engaging bar, means for securing the horizontal bar in its engaging position and for connecting the lower end of the chain with the said horizontal bar, and means for adjustably connecting the upper end of the chain with the upper horizontal door to enable the upper door to be closed tightly or arranged partially open to allow for ventilating the car.

11. The combination with a car having a door opening, of a lower or main door composed of sectional doors having hinged vertical sections, an upper horizontal door hinged at the top of the door opening and overlapping the lower or main door, a pivoted door engaging bar mounted on the lower or main door and arranged horizontally on the same and engaging each of the sections thereof and having a fixed projecting tongue or portion, means mounted on the lower or main door and co-operating with the said bar for securing the lower or main door in its closed position, a hasp member detachably secured to the said tongue or projecting portion, and means for adjustably connecting the hasp member with the upper door for securing the latter tightly in its closed position or partly open to ventilate the car.

12. The combination with a car having a door opening, of a lower or main door composed of sectional doors having hinged vertical sections, an upper horizontal door hinged at the top of the door opening and overlapping the lower or main door, a horizontal door engaging bar pivotally mounted on the lower or main door and engaging each of the sections thereof and having a fixed projecting portion or tongue, means mounted on the lower or main door and co-operating with the said bar for securing the lower or main door in its closed position, a hook carried by the upper door, a chain detachably engaging the hook of the upper door to enable the latter to be held tightly closed or partly open to ventilate the car.

said chain extending along the lower or main door and provided with a hasp member having an opening receiving the projecting portion or tongue of said bar, and 5 means for securing the hasp member on the tongue or projecting portion.

13. The combination with a car having a door opening, of a lower or main door composed of sectional doors having hinged vertical sections, an upper horizontal door hinged at the top to the door opening and overlapping the lower or main door, a horizontal door engaging bar pivotally mounted on the lower or main door and engaging the 10 sections thereof and having a projecting portion or tongue, means mounted on the lower or main door and coöoperating with the said bar for locking the lower or main door in its closed position, a hook carried by the 15 upper door, a chain detachably and adjustably engaging the hook of the upper door to enable the latter to be secured tightly in its closed position or partly open to ventilate the car, said chain extending along the lower or main door and provided with a hasp member having an 20 opening through which extends the said projecting portion or tongue, and spaced guides mounted on the lower or main door and receiving the chain.

25 14. The combination with a car having a

door opening, of a lower or main door composed of sectional doors having hinged vertical sections, an upper horizontal door hinged at the top of the door opening and overlapping the lower or main door, a horizontal door engaging bar pivotally mounted on the lower or main door and engaging the sections thereof and having a projecting tongue, a hook carried by the upper door, a chain detachably and adjustably engaging 30 the hook of the upper door to secure the latter tightly in its closed position and also partly open to ventilate the car, said chain extending along the lower or main door and provided with a hasp member having an 35 opening receiving the projecting tongue of said bar, an arm carried by the hasp member and provided with an opening, and a locking pin also mounted on the hasp member and engaging the tongue and provided with an 40 opening, the opening of the arm and the pin being arranged to receive a car seal.

In testimony, that I claim the foregoing as my own, I have hereto affixed my signature in the presence of two witnesses.

PHILIP C. MERKER.
